JOHN A. MAKER, OF DULUTH, MINNESOTA.

CLOSURE FOR DISPENSING PASTE-TUBES.

1,227,638.

Specification of Letters Patent.

Patented May 29, 1917.

Application filed December 10, 1915. Serial No. 66,134.

To all whom it may concern:

Be it known that I, JOHN A. MAKER, a citizen of the United States, residing at Duluth, in the county of St. Louis and State of Minnesota, have invented certain new and useful Improvements in Closures for Dispensing Paste-Tubes, of which the following is a specification.

This invention relates to closures for dispensing tubes such for example as tubes designed to contain tooth paste and the like.

The ordinary tooth paste tube is provided with a closure cap which is removably threaded on to the discharge spout of the tube and which must be completely removed in order to permit of discharge of the contents of the tube. Such closures, however, present the disadvantage that one is likely to forget to replace the cap, leaving the discharge spout uncovered and resulting in hardening or drying of the contents in the spout or contamination of the contents by insects, dust, and dirt. Such closures present the further disadvantage that the caps are liable to become lost or dropped into toilet fixtures from which their recovery is difficult. The present invention, therefore, aims to provide a closure of the class described so constructed that the contents of the tube may be discharged without the necessity of removing the closure bodily from the spout and, in fact, the invention contemplates so assembling the closure with the spout that it cannot be removed without force or destruction of the closure and spout. Consequently, the closure of the present invention cannot be lost and its presence upon the spout serves as a reminder to the user of the tube to return the closure to closed position after the desired quantity of paste has been discharged from the tube.

In the accompanying drawings:

Figure 1 is a perspective view illustrating the closure embodying the present invention embodied in the construction of an ordinary collapsible paste tube.

Fig. 2 is a vertical longitudinal sectional view through the closure and spout.

Fig. 3 is a horizontal sectional view on the line 3-3 of Fig. 2.

In the drawings the numeral 1 indicates the collapsible tube in which the paste or other substance to be dispensed is contained and 2 indicates the discharge end of the said tube, which end is provided with a tubular discharge spout 3 having its outer end closed

as indicated by the numeral 4. Near its juncture with the closed end 2 of the tube 1 the discharge spout 3 is provided with a longitudinally extending discharge orifice 5 through which the paste may issue in a ribbon-like stream upon compression of the tube 1 and may be laid in this form upon the tooth brush. The spout 3 is exteriorly threaded near its closed outer end as indicated by the numeral 6, the threads extending down the exterior of the spout but a short distance so that the exterior of the spout will be cylindrical a considerable distance above the discharge orifice 5 for a purpose to be presently explained.

The closure for the spout is in the nature of a cap comprising a substantially cylindrical body 7 which is closed at its outer end as indicated at 8 and adjacent the said end 75 is interiorly threaded as indicated at 9, the cap being applied to the discharge spout 3 with its threads 9 engaging the threads 6 of the said spout and the parts are so proportioned that when the cap is threaded 70 down to the position shown in Fig. 2 of the drawings, the lower edge 10 of the wall of the cap will bear snugly against the upper surface of the closed end 2 of the tube 1 and completely surround the lower end of 85 the discharge spout 3, thereby preventing entrance of air and water into the cap and into the tube through the orifice 5. It will be understood at this point, that by unthreading the cap until the threads upon 90 the interior of the cap are disengaged from the threads upon the discharge spout 3, the cap may be slid outwardly upon the said spout so as to uncover the orifice 5 and permit of discharge of the contents of the tube. 95

In order to prevent complete removal of the cap from the discharge spout after its threads have moved out of engagement with the threads upon the said spout, and yet permit of free turning of the cap upon the 100 spout so that the threads may be again caused to coöperate and the cap may be closed, an annular flange 11 is formed upon the inner surface of the cap 7 at the lower end of the said cap and the spout is reduced 105 in diameter below the threads 6 so as to form a shoulder 12, and it will be understood that when the cap has been completely unthreaded from the outer end of the spout and is slid outwardly, the flange 11 will engage with the shoulder 12 upon the spout and further outward movement of

the cap will be prevented although the cap may have swiveling movement upon the said spout. By reference to Fig. 2 of the drawings it will be observed that the distance 5 between the lower end of the spout 3 and the upper end of the orifice 5 is less than the distance between the flange 11 and the shoulder 12 so that when the flange 11 is in engagement against the shoulder the orifice 5 10 will be completely uncovered.

Having thus described the invention, what is claimed as new is:

1. The combination with a container of a discharge spout therefor provided in its side 15 with a discharge orifice and exteriorly threaded at its outer end, the outer end of the spout being closed, a closure cap interiorly threaded at its outer end and fitted upon the said spout and arranged to have its 20 threads coöperate with the threads upon the spout when the cap is in closed position and to disengage from the said threads upon the spout as the cap is moved to open position outwardly upon the spout, and means upon 25 the cap arranged to coöperate with the threads upon the spout to limit the outward movement of the cap after disengagement of its threads from the threads upon the spout.
2. The combination with a container, of 30 a tubular discharge spout therefor completely closed at its outer end and exteriorly threaded at its said outer end, the said spout inwardly of its threaded portion being exteriorly cylindrical and smooth and the 35 spout being provided relatively close to its juncture with the container with a discharge opening, a closure cap interiorly threaded

at its outer end and arranged to have its threads to coöperate with the threads upon the spout when the cap is in closed position 40 and to disengage from the threads upon the spout when the cap is moved to open position outwardly upon the spout, the said cap inwardly of its threaded portion being 45 interiorly smooth and being provided at its inner end with an inturned annular flange the edge of which is designed to rotatably and slidably contact the exterior surface of the spout inwardly of the threaded portion of the said spout.

3. The combination with a container, of a tubular discharge spout therefor completely closed at its outer end and at its said outer end exteriorly threaded and being provided at the inner end of its threaded portion with a circumscribing shoulder, the spout being exteriorly reduced in diameter between its said shoulder and the point of junction with the container, the said reduced portion of the spout at its inner end being 60 formed with an orifice and the cap for the spout being closed at its outer end and interiorly threaded at its said outer end to coact with the threaded outer end of the spout, the said cap at its inner end being 65 formed with an inwardly projecting annular flange arranged to coöperate with the said shoulder to limit the outward movement of the cap from the spout, the inner edge of the said flange contacting the surface of the reduced portion of the spout.

In testimony whereof, I affix my signature.

JOHN A. MAKER. [L.S.]
